(57) **CLAIM**

The ornamental design for an exercise device, as shown and described.

DESCRIPTION

FIG. 1 is a front perspective view of an exercise device. FIG. 2 is a front view of the exercise device. FIG. 3 is a rear view of the exercise device. FIG. 4 is a left side view of the exercise device of which the right side is a mirror image. FIG. 5 is a right side view of the exercise device. FIG. 6 is a bottom view of the exercise device; and, FIG. 7 is a rear perspective view of the exercise device. The contour lines shown in lighter weight with breaks as well as the other broken lines shown in the figures form no part of the claimed design.

1 Claim, 7 Drawing Sheets
